CLAIM

The ornamental design for a lighting fixture, as shown and described.

DESCRIPTION

FIG. 1 is a perspective view of a lighting fixture showing our new design;

FIG. 2 is a front view thereof, the rear view being identical to the front view;

FIG. 3 is a right side view thereof, the left side view being identical to the right side view;

FIG. 4 is a top view thereof;

FIG. 5 is a bottom view thereof;

FIG. 6 is an enlarged cross-sectional view taken along line 6—6 in FIG. 2 with the internal parts omitted; and,

FIG. 7 is an enlarged view of an indicated portion in FIG. 6. The portions shown in double cross-hatched lines in FIGS. 6 and 7 are transparent.
